US00D847131S

(12) **United States Design Patent** (10) **Patent No.:** **US D847,131 S**
(45) **Date of Patent:** **** Apr. 30, 2019**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/578,144**

(22) Filed: **Sep. 19, 2016**

Related U.S. Application Data

(63) Continuation of application No. 29/471,707, filed on Nov. 4, 2013, now Pat. No. Des. 766,889, which is a continuation of application No. 29/453,552, filed on Apr. 30, 2013, now Pat. No. Des. 692,881, which is a continuation of application No. 29/431,730, filed on Sep. 11, 2012, now Pat. No. Des. 681,032.
